UNITED STATES PATENT OFFICE.

SANTO E. P. MATACOTTA, OF NEW YORK, N. Y.

HEEL.

1,142,598.

Specification of Letters Patent.

Patented June 8, 1915.

Application filed January 9, 1913. Serial No. 740,981.

To all whom it may concern:

Be it known that I, SANTO E. P. MATA-
COTTA, a citizen of the United States, and a
resident of the city of New York, borough
of Manhattan, in the county and State of
New York, have invented a new and Im-
proved Heel, of which the following is a
full, clear, and exact description.

This invention relates to improvements in
heels, and has for an object to provide an
improved structure which will allow a part
of the heel to be removed and replaced
whenever desired.

A furher object of the invention is to
provide a heel formed with a rotary mem-
ber and with a clamping structure which is
adapted to clamp the rotary member in any
desired position for presenting a perfectly
constructed rear heel structure notwith-
standing the wear on certain parts of the
heel.

A still further object of the invention is
to provide in a heel plate a clamping struc-
ture designed to engage a rubber or leather
heel, or a movable heel portion of any kind,
so as to hold the same properly in place, but
to provide when desired, an adjustment
thereof in order that any worn part of the
heel may be moved to a point where the
wear is not so severe.

In carrying out the objects of the invention,
an ordinary heel structure of any de-
sired kind is built up for a short distance
at the bottom of the shoe, and then the im-
proved structure is applied thereto, which
is formed with a disk member and a squared
portion having an arc-shaped recess therein
for accommodating part of the disk mem-
ber. The disk member or part of the heel
is connected with a clamping plate which
accommodates a clamping screw designed to
be threaded into a suitable socket member
arranged in the built up heel structure so
that the disk part of the heel may be rig-
idly clamped against movement whenever
desired, or may be released so as to be ro-
tated or removed.

A practical embodiment of the invention
is represented in the accompanying draw-
ings forming a part of this specification, in
which similar characters of reference indi-
cate corresponding parts in all the views.

Figure 1 is a fragmentary sectional view
through a shoe showing the shoe and heel,
the heel embodying the invention; Fig. 2
is a bottom plan view of the structure shown

in Fig. 1; Fig. 3 is a view similar to Fig. 2,
except that the rotary wearing member is
removed; Fig. 4 is a top plan view of the
retaining plate embodying certain features 60
of the invention; and Fig. 5 is a bottom plan
view of the plate shown in Fig. 4.

Referring to the accompanying drawings
by numerals, 1 indicates a shoe of any de-
sired kind provided with the usual heel 2. 65
When using the improved heel structure
embodying the present invention, the heel
2 is preferably made low so that the same,
together with the rotary wearing member 3
will give the correct height to the entire 70
heel structure. The rotary wearing mem-
ber 3 co-acts with a filling portion 4 which
may be built up or formed of one piece, as
desired, the same having a desired shape or
contour to agree with the particular design 75
of the heel desired. On one side of the fill-
ing member 4, the same is provided with an
arc-shaped notch or recess 5 which is designed
to accommodate the rotary wearing member
3, as clearly shown in Fig. 2. The rotary 80
wearing member 3 is made of such a size
as to mate with the rear wall 6 of the heel
2 in order to give a correct appearance to
the heel when taken with member 4. In
constructing the heel 2, an opening is pro- 85
vided in which a metallic socket member 7
is placed and held in place by suitable nails
or screws 8. The socket member 7 is thread-
ed so as to receive a clamping screw 9 which
is formed with notches 10 so as to receive 90
a suitable key or wrench for applying and
removing the screw.

Having thus described my invention, I
claim as new and desire to secure by Letters
Patent:—

1. In a device of the character described,
the combination with the heel of a shoe, of
a threaded socket member arranged therein,
a notched filling member connected with
said heel, and a rotatable disk shaped wear- 100
ing member fitting into said notched mem-
ber for completing the bottom surface of
said heel, said rotating wearing member be-
ing formed with a clamping plate having a
plurality of turned up fingers, and a wear- 105
ing body held to said plate by said fingers,
and a clamping screw engaging said plate
and said socket member for clamping the
plate rigidly against the socket member.

2. A device of the character described, 110
comprising a rotating wearing member
adapted to be arranged on the bottom of the

heel of a shoe, said wearing member being formed with a clamping plate having a plurality of bent-over ears arranged at the periphery, and a plurality of clamping ears 5 arranged between the periphery and the center, a flexible wearing member clamped in place by the ears arranged between the periphery and the center, and a resilient body surrounding said wearing member and the 10 ears extending from the periphery of the

plate, said plate being provided with an aperture for receiving a clamping member.

In testimony whereof I have signed my name to this specification in the presence of two subscribing witnesses.

SANTO E. P. MATACOTTA.

Witnesses:
